United States Patent Office

Des. 195,688
Patented July 16, 1963

195,688

APPLIANCE HANDLE

Dominic J. De Fano, River Grove, Ill., assignor to
McGraw-Edison Company, Milwaukee, Wis., a corpora-
tion of Delaware

Filed Oct. 26, 1962, Ser. No. 72,277

Term of patent 14 years

(Cl. D44—29)

FIG. 1.

FIG. 2.

FIG. 3.

FIG. 4.

FIG. 1 is a perspective view showing the front, top and side of an appliance handle embodying my new design;
FIG. 2 is a top view thereof;

FIG. 3 is a front elevational view thereof, with a fry pan or the like shown in broken lines for illustrative purposes only; and

FIG. 4 is a side view thereof.

The dominant features of my design reside in the portions shown in full lines.

I claim:

The ornamental design for an appliance handle, as shown and described.
